UNITED STATES PATENT OFFICE.

CHARLES H. MUCKENHIRN, OF DETROIT, MICHIGAN, ASSIGNOR, BY MESNE ASSIGNMENTS, TO THE STANDARD SANITARY MANUFACTURING COMPANY, OF PITTSBURGH, PENNSYLVANIA, A CORPORATION OF NEW JERSEY.

WATER-CLOSET BOWL.

1,132,109.

Specification of Letters Patent. Patented Mar. 16, 1915.

Application filed July 11, 1910. Serial No. 571,309.

To all whom it may concern:

Be it known that I, CHARLES H. MUCKENHIRN, a citizen of the United States, residing in Detroit, county of Wayne, State of Michigan, have invented a certain new and useful Improvement in Water-Closet Bowls, and declare the following to be a full, clear, and exact description of the same, such as will enable others skilled in the art to which it pertains to make and use the same, reference being had to the accompanying drawings, which form a part of this specification.

This invention relates to water closet bowls, and has for its object an improved bowl provided with a discharge conduit by means of which the contents of the bowl are discharged rapidly, certainly, quietly, without break in siphon action after the siphon action has been once started, and without return flow.

The invention is equally applicable to the jet siphon or to the form in which the starting action is accomplished by raising the head of water without the jet. In either form, at the beginning of the action the water rises in the short leg with a force that gradually diminishes as the action continues, and at the beginning of the action the water rising through the short leg rises in greater quantity than at a later period and the quantity gradually diminishes. In order that the siphon action may continue as long as possible the outlet from the long leg must be made as small as possible. In order that the siphon action may be constant without back flow provision must be made below the dam to either carry off or store all water that flows over the dam during the period of high rate flow. Moreover, if the jet force be added to the regular siphon action this excessive flow will be great during the first part of the action at the very time when a return flow will be liable to return to the bowl those parts of its contents which it is especially desirable to remove, and after a return flow has taken place there is a liability that such contents will not wash out at all during the present period of siphon action. Furthermore, it is extremely desirable that the passage should be no where smaller than it is at the opening into the short or up leg, and therefore the results must be accomplished without drawing in

the walls or using the constricting means that diminish the cross-sectional area of the outlet. The outlet in the bowl which embodies my invention is increased in cross sectional area immediately below the dam, and there is here provided a chamber which will receive and store such excess of water as cannot immediately run away, and below this chamber I employ means which partially neutralize the acceleration due to the action of gravity; this is done by so constructing the conduit walls as to stop the water, or form eddy currents therein and thus form just below the enlarged part of the conduit a water plug that holds the air out from the chamber while the water in the chamber is itself constantly sinking and thus the plug extends upward to the spill-way of the dam. The exact proportioning of parts is determined from a consideration of the size of the inlet, the height or head in the bowl, the distance below this of the final outlet, the height of the tank, the size of discharge from the tank into the cavity of the bowl, the size of discharge orifice of the jet if there be one, and the head of water under which the jet acts. Each of these factors may be changed and whenever any one is changed other features must be changed to correspond in order to produce good results, but the broad features effecting good results are those which provide for the receipt and temporary storage in a chamber just below the dam of that quantity which the outlet cannot immediately carry away, and so constructing the final outlet that it will hold back the water in this chamber and keep the chamber full enough to maintain the siphon action until the bowl and the tank are properly discharged. The result is accomplished by the bowl shown and described in the accompanying drawings, in which:

Figure 1, shows a vertical longitudinal section with vertical outlet, called in trade a straight outlet. Fig. 2, is a horizontal section at line, a, a of Fig. 3.

The invention applied to a siphon jet bowl is shown in Figs. 1, 2.

In the drawing I show a bowl with the ascending leg 7. The body of the bowl is made in the ordinary form with the usual flushing rim and the ascending leg 7 of the

discharge outlet which is round or substantially round in cross section. The descending leg 8 is curved forwardly until the rear line of the discharge is under or substantially under the spillway of the dam 6; the enlarged chamber is reduced to the normal sized outlet 5 by an abrupt reduction. This curve and collar accomplish the result of overcoming the acceleration of the speed of 10 the water due to gravity and cause the water to form a plug at the bottom of the chamber which prevents the introduction of air from below, but furnishes a chamber large enough to receive and retain the water during the 15 period that its flow through the leg 7 is above the normal siphon flow. If the jet be omitted the principle of construction is the same, but the capacity of the chamber in the down leg need not be so great, the principal 20 feature of the invention being the provision of a chamber immediately below the dam of the siphon which has a capacity to receive all water which runs over the dam; co-acting with this chamber is some adequate 25 means for so impeding the discharge from the chamber as to form a constant plug of water that continues in place so long as wa-

ter is running over the dam into the chamber, that is, the chamber is to empty only with the speed of the lowest speed of inflow 30 and the chamber shall temporarily store excess water that enters because of a faster speed of inflow.

What I claim is:—

A closet bowl of the character described, 35 of integral formation having a rearwardly curved up leg, a down leg enlarged throughout its length and having a reversed curve, said down leg terminating immediately under the spiller of the bowl and at its terminal having a restricted outlet located at its rear wall, there being an offset located adjacent said outlet at the front wall with which the water in its downward progress contacts and is deflected transversely of the leg whereby to ball up the water at the outlet and form a water plug. 40

In testimony whereof, I sign this specification in the presence of two witnesses.

CHARLES H. MUCKENHIRN.
